Attorney.

UNITED STATES PATENT OFFICE

GEORGE D. OVERHOLTZ, OF FAIR OAKS, PENNSYLVANIA, ASSIGNOR TO McCLINTIC-MARSHALL COMPANY, OF PITTSBURGH, PENNSYLVANIA, A CORPORATION OF PENNSYLVANIA

OUTDOOR ADVERTISING STRUCTURE

Application filed June 16, 1930. Serial No. 461,271.

This invention relates to improvements in outdoor advertising structures, and more particularly to all-metal bulletin structures and attachments therefor.

In structures of the character designated, it is customary to employ a hollow sheet metal molding surrounding the panels of the bulletin and carried by the supporting framework. To provide suitable reinforcing for the molding, longitudinal angle members are positioned therein, as particularly shown and described in my companion application Serial No. 461,270.

For the purpose of illuminating the bulletin structure, it is the general practice to position lights in front of the bulletin, the lights being projected therefrom by means of suitable conduits, the latter being secured to the top molding of the bulletin. When, as in the present case, a hollow sheet metal molding is employed, it becomes difficult to secure the conduit thereto without causing a distortion or warping of the sheet metal.

The present invention has among its objects to provide new and improved means associated with the hollow metal molding and its reinforcements, whereby illuminating fixtures may be readily applied and securely attached to said molding without injury thereto.

My invention contemplates the use of an anchor member or the like within the hollow metal molding, clips for the conduits of the illuminating fixture, and bolts or screws passed through said clips, anchor member, and the molding for rigidly securing said fixture in place.

It is a further object of my invention to provide said clips, anchor member and metal molding with a plurality of aligned slotted openings to afford adjustability in the mounting of the illuminating fixture.

In the accompanying drawings, which illustrate a preferred embodiment of my invention:

Fig. 1 is a front perspective view of a portion of an all-metal bulletin structure, partly broken away to disclose details;

Fig. 2, a detail section taken on the line II—II of Fig. 1; and

Fig. 3, a cross section taken on the line III—III of Fig. 2.

Referring to the drawings, 2 designates uprights or posts preferably in the form of angle members, and constituting part of a steel framing upon which the bulletin proper is erected. Such framing also includes horizontal angle members 3 secured to the uprights 2 in any suitable manner. 4 designates panels secured to the framework, a number of which are employed to provide a surface to receive the advertisement.

A section of the top molding or cornice is shown at A, said molding serving as a border for the panels 4. The molding, as illustrated, is formed of sheet metal, cut and bent into the desired configuration, and includes a substantially rectangular capping portion 6, a receiving portion 7, and a depending rectangular portion 8.

The molding A is supported at each upright 2 by means of a mounting, generally designated 9, said mounting including a main bracket member 10, a supplemental bracket member 11, and Z-brackets or Z-members 12 and 13.

Reinforcing angle members 14 extend longitudinally of the molding A and within the capping portion 6 thereof. The forward angle member 14 has a flange thereof entered between the main and supplemental bracket members 10 and 11 respectively, and the rear angle member 14 has a flange thereof entered between supplemental bracket member 11 and the Z-bracket 12. Such construction is more fully described in my companion application supra.

An illuminating fixture shown at B has a conduit 15 adapted to extend over the molding A and in front of the bulletin a sufficient distance to position the fixture B so as to adequately illuminate the panels 4. The conduit then passes behind the bulletin structure for connection with a source of electrical energy.

For the purpose of attaching the conduit 15 to the molding A, and particularly to the upper portion of the capping 6, I provide spaced-apart clips or brackets 16, each having a curved portion 17 for embracing the

conduit. Said clips are further provided with lateral extensions 18 having a slotted opening 19 therethrough. Spaced - apart rows of slotted openings 20 are formed in the upper portion of the capping 6 of the molding A between the angle members 14, and headed bolts or screws 21 are provided for securing the clips on the molding, said bolts passing through the openings 19 of the clips and any of the openings 20.

5 An anchor member 22 in the form of a bent metal plate is designed to be positioned beneath the upper portion of capping 6 and extend between the reinforcing angles 14 for stiffening the capping and providing a bearing for the nuts 23 of screws 21.

10 Said anchor member is formed with spaced-apart rows of slotted openings 24 in alignment with the rows of openings 20 in the capping portion 6 of the molding A. In addition, the anchor member is provided with a depending hook flange 25 designed to be positioned over a depending flange *a* of one of the reinforcing angle members 14.

15 Thus, it will be seen that the fixtures B may be readily positioned on the bulletin board and secured to the molding A at any desired point between the uprights 2, without injury to the said molding. By means of the slotted 20 openings in the capping 6, anchor member 22 and the clips 16, the conduits 15, and therefore the illuminating fixtures B, may be adjusted to the desired location.

25 While I have shown and described my invention in connection with the mounting of illuminating fixtures, it will be understood that such invention is broader in its scope and may be applied for mounting other bulletin attachments, as for example, imprints.

30 I claim:

35 1. In an outdoor advertising structure, the combination with a hollow metal molding, of a reinforcing member therein, means for mounting and securing an attachment thereon including an adjustable clip disposed on the exterior of the molding, an anchor member disposed within the molding, means on the anchor engaging the reinforcing member, and means for adjustably securing the clip to the molding.

40 2. In an outdoor advertising structure, the combination with a hollow metal molding, of reinforcing angle members therein, an attachment to be mounted on said molding, and means for securing said attachment to the molding including an anchor member within the molding, said anchor member having a hook flange for engaging one of said angle members.

45 3. In an outdoor advertising structure, the combination with a hollow metal molding, of reinforcing angle members therein, an illuminating fixture including a conduit to be mounted on said molding, clips engaging the conduit, an anchor member within the mold-

50 ing engaging one of said angle members, and attaching means passed through the clips, molding and anchor member.

55 4. In an outdoor advertising structure, the combination with a hollow metal molding, of reinforcing angle members therein, an illuminating fixture including a conduit to be mounted on said molding, clips engaging the conduit, an anchor member within the molding engaging one of said angle members, slotted openings in the clips, molding and anchor member, and bolts passed through said openings.

60 5. In an outdoor advertising structure, the combination with a hollow metal molding, of an illuminating fixture for attachment thereto, and means for securing the fixture to the molding including a member disposed within the molding, a clip, and means passed through the molding, clip and said member.

65 In testimony whereof I affix my signature.

GEORGE D. OVERHOLTZ.
